UNITED STATES PATENT OFFICE.

BARTON BERKLEY HILL, OF LOWELL, MASSACHUSETTS.

RAILWAY CONSTRUCTION TRAIN OR CARRIAGE.

SPECIFICATION forming part of Letters Patent No. 325,246, dated September 1, 1885.

Application filed October 1, 1884. (No model.)

To all whom it may concern:

Be it known that I, BARTON BERKLEY HILL, of Lowell, in the county of Middlesex, of the Commonwealth of Massachusetts, have invented 5 a new and useful Improvement in Railway Construction - Trains or Carriages Therefor; and I do hereby declare the same to be described in the following specification, and represented in the accompanying drawings, of 10 which—

Figure 1 is a side elevation of a train embodying my invention, the nature of which is defined in the claims hereinafter presented. The train, as shown, consists not only of a locomotive platform-car and a supplementary platform-car provided with mechanism for advancing the rails upon them lengthwise of them, but one or more ordinary platform-cars, my invention having reference to the said locomotive and supplementary platform-car. Fig. 15 2 is a top view; Fig. 3, a side elevation; Fig. 4, an under side view; Fig. 5, a front end view on an enlarged scale of the locomotive platform-car. Fig. 6 is a side elevation of the 20 supplemental car. Fig. 7 is a top view, Fig. 8, a front elevation, and Fig. 9 a side view, of 25 one of the adjustable brackets of the locomotive-car, the latter figure exhibiting railway-track rails as applied to such brackets.

The "locomotive platform-car" has its platform A supported near its front end by a swiveling four-wheeled truck, B, while near its rear end it is sustained by four wheels, a, which are driving-wheels, two of which, on 30 each side of the car, are connected by a connection-rod b. Furthermore, for operating these wheels, the car is furnished with two steam-engines, c, a boiler, d, and a tender-tank, e, of any suitable construction. Furthermore, the car is furnished with two auxiliary steam-engines, f, the connecting-rods g of whose pistons are applied to cranks h, extending from a shaft, i, which has between the said two cranks a third crank, k. To this latter crank, and to a series of others, l, projecting from a series of other parallel shafts, m, arranged under and across the platform, as shown, a long connection-bar, m', is jointed, the whole being so as to cause all the shafts m 45 to revolve simultaneously with and to be revolved by the shaft i.

On each of the shafts m there are fixed two broad wheels, n, each of which extends up through the platform and somewhat above it, as shown, such wheels being disposed in two 55 parallel ranges.

To the shaft i there are two other cranks, o, which, by means of two auxiliary connection-rods, p, extending nearly to the rear end of the car, couple with a series of cranks, q, 60 of other shafts, r, arranged as represented, each of such shafts r having upon it a broad wheel, n, such as hereinbefore mentioned, it being, like the others, extended up through and somewhat above the platform. All the 65 wheels n are in two parallel ranges, each of which, when a rail is laid upon it and the several wheels of the range are in operation, is intended to advance such rail from the rear to the front end of the car or to a position between two ends of the car. The rails and ties 70 are to constitute the load of the ordinary platform-car in rear of the supplementary car.

In Figure 1 the locomotive platform-car is shown at L, the supplementary car at M, and the auxiliary car or cars at N. The supplementary car is furnished at or near one end of it with a steam-engine, O, its boiler P, and tender-tank Q, such being to operate two ranges of broad wheels, n, arranged in the platform of 80 the car, and provided with mechanism for simultaneously revolving them, such mechanism being like that of the wheels n of the locomotive-car, and to be operated by the steam-engine O suitably applied to it. The two 85 ranges of broad wheels n of each car are at the same distance asunder, in order that when a rail may be taken from the foremost of the auxiliary cars and laid on one of the ranges of wheels of the supplemental car, such rail, 90 provided such wheels may be in revolution, will be moved along the range and by it be transferred to the next adjacent range of the locomotive-car, to be by it advanced still farther. These ranges of wheels are to save the 95 labor of men that might otherwise be required to transfer each rail, or two or more connected rails, along the platforms of the cars.

The locomotive-car, near its front end, has a shaft, t, whose journals are supported in two 100 standards, u. This shaft carries two friction-wheels, v, provided with brakes w, applied to

a lever, x , all being arranged as represented. Furthermore, there extend from the shaft two long arms, y , each of which has a chain, z , depending from it at its outer end. On the 5 shaft is a spiral spring, a' , which, suitably connected to it and the platform, serves to overbalance the arms and raise them to an inclined position, as represented. Each chain z , at its lower end, has a stirrup, tongs, or a grapple, b' , 10 fixed to it for seizing a rail and supporting it while it may be in the act of being moved off the locomotive platform-car and deposited on the laid ties of track. By means of the brakes and the friction-wheels the descent of the rail, 15 or combined rails, can be regulated as may be required. There projects from each side of the locomotive platform-car a series of vertically-adjustable brackets, E . Each of these brackets is supported between two guides, F , so as to 20 be capable of being slid vertically, there being in the bar c' of the bracket a series of holes, d' . On the bracket having been adjusted in altitude, a pin or bolt inserted in the hole next above the guides will serve, when resting 25 on them, to hold the bracket in position. On each range of brackets two lines of rails, d^2 , are laid in parallelism and held to the brackets by suitable chairs or devices. The supplementary platform-car may also be provided, 30 in like manner, with such brackets and rails, or it may have the brackets above, which may be applied so as to be capable of being turned back flatwise against the side of the car—that is, into positions as shown at d^3 in Fig. 6. 35 Each set of rails d^2 is provided with one or more trucks or carriages, e' , for transporting the ties, which are shown at f' as loaded on such trucks. The object of having the brackets adjustable or movable vertically is to admit of the railway-truck on them being arranged horizontal or about so, when the construction-train may be either on an "up" or 40 "down" grade.

The locomotive platform car is represented 45 as having on its platform a box, G , for hold-

ing the tools, fish-plates, bolts, or other devices usually required in laying a railway-track. As the track may be laid the construction-train is to be advanced on it, the rails and ties, &c., being advanced automatically on the 50 locomotive and supplementary platform-cars. Guards n^2 are applied to the said cars on each side of the ranges of wheels n , as shown in Figs. 2 and 5, to keep the rails while being advanced from running off the wheels n . 55

I claim—

1. The locomotive platform-car provided with a steam engine and boiler, or mechanism for moving such car on a railway-track, and also having to one or each side of its platform 60 a series of brackets, and a railway-track thereon provided with one or more wheeled trucks, all being substantially as set forth.

2. The locomotive platform-car provided not only with a steam engine and boiler, or 65 mechanism for moving the car on a railway-track, and with one or more sets of broad wheels extending throughout lengthwise of it, and having mechanism for simultaneously revolving them, but with a series of brackets, 70 adjustable as described, applied to one or each of the sides of the car, and having laid upon it, the said series, a railway-track furnished with one or more trucks or carriages, all being substantially and for use as represented. 75

3. The locomotive platform-car provided not only with a steam engine and boiler, or mechanism for moving such car upon a railway, and also with a series of broad wheels arranged in it, and having mechanism for simultaneously revolving them, as described, 80 but with a shaft and arms projecting therefrom, and with friction wheels and brakes, and a spring to the shaft, such shaft being near one end of the car, and all being substantially and for use as set forth. 85

BARTON B. HILL.
